[57] CLAIM

The ornamental design for a comb for carpet sweeper brushes, substantially as shown and described.

DESCRIPTION

FIG. 1 is a top plan view of a comb for carpet sweeper brushes showing my new design;

FIG. 2 is a bottom plan view thereof;

FIG. 3 is a front side elevation thereof;

FIG. 4 is a rear side elevation thereof with the ends reversed;

FIG. 5 is an end elevation thereof taken from the left end of FIG. 3; and

FIG. 6 is an end elevation thereof taken from the right end of FIG. 3.
